UNITED STATES PATENT OFFICE.

ABRAM C. MOTT, JR., OF PHILADELPHIA, PENNSYLVANIA, ASSIGNOR TO ABRAM COX STOVE COMPANY, OF PHILADELPHIA, PENNSYLVANIA, A CORPORATION OF PENNSYLVANIA.

MOLDING-FLASK.

1,081,251.

Specification of Letters Patent. Patented Dec. 9, 1913.

Application filed April 19, 1912. Serial No. 691,793.

To all whom it may concern:

Be it known that I, ABRAM C. MOTT, Jr., a citizen of the United States, residing in Philadelphia, Pennsylvania, have invented 5 certain improvements in Molding-Flasks, of which the following is a specification.

My invention relates to certain improvements in flasks for sand molding; the invention relating particularly to the type of 10 flask which is removed from the molded sand after the mold is formed and before the metal is poured so as to dispense with a large number of flasks.

The invention also relates to certain improvements in flasks made in two or more parts.

The main object of the invention is to provide means for retaining the sand in the flask while the flask is being manipulated so 20 that the flask can be turned without discharging the sand; yet allowing the flask to be removed from the sand mold when completed.

A further object of the invention is to 25 provide means for removing the cope from the drag and from the pattern board.

A still further object of the invention is to provide means for coupling an additional section to a flask when necessary.

30 The invention also relates to certain details which will be fully described hereafter.

In the accompanying drawings:—Figure 1, is a side view of a flask illustrating my invention; Fig. 2, is a plan view of a portion 35 of the flask illustrated in Fig. 1; Fig. 3, is a plan view of the entire flask, drawn to a reduced scale; Fig. 4, is a sectional view on the line *a—a*, Fig. 3; Fig. 5, is a sectional view of a portion of the flask on the line 40 *b—b*, Fig. 3; Fig. 6, is a sectional view on the line *a—a*, Fig. 3; showing the sand supporting frame retracted; Fig. 7, is a plan view of the support for the sand of the mold; Fig. 8, is a perspective view of the 45 operating lever for the sand support; Fig. 9, is a perspective view of one of the sliding blocks; Fig. 10, is a perspective view of the eccentric for operating the levers for separating the flask; Fig. 11, is a detached perspective view of the two separating levers; Fig. 12, is a view of a modification of the 50 means for moving the independent members of the sand support; Figs. 13, 14, and 15, are diagram views illustrating the method 55 of using my improved molding flask; and

Fig. 16, is a sectional view on the line *b—c*, Fig. 2. Fig. 17, is a side view of the flask, showing the modification illustrated in Fig. 12 applied to the flask.

Referring to the drawings, 1 is the cope 60 of the flask, flanged at the upper and lower edge in the present instance. 2 is the drag, also flanged at the upper and lower edge. Located between these two sections of the flask is the match plate 3 upon which the 65 pattern 4 is mounted. The pattern, in the present instance, extends into the cope section 1 and mounted on the cope section is an extension 5, which is used when the pattern is of such a height as to warrant the 70 introduction of more sand between the end of the pattern and the top of the mold. The extension 5 has lips 8 which extend over the flanges 9 on the cope section; there being lips on three sides, as illustrated in Figs. 4 75 and 5. On the other side is a key 10, which is driven into an undercut slot in the extension 5 and bears against the end of the flange of the cope section. When the key is 80 removed, the extension can be readily detached from the cope section.

Adapted to slide in the lower portion of the cope section 1 is a sand retaining frame 11 made in four sections as clearly shown in Fig. 7. The sections 12, 12 are beveled 85 at each end, as shown at 13, and rest against the inclined portions 14 of the sections 15. The sections 12 are slotted at 21 for the guide pins on the cope section and the sections 15 are also slotted for the reception of 90 the guide pins. In the sections 15 are openings 19 for the reception of bolts 18 on the blocks 17 which are mounted on the lower flange of the cope section 1. The bolts 18 on the blocks also enter inclined slots 16 in the sections 12 so that when the blocks 95 are moved both sections 12 and 15 are forced toward or from the center of the flask.

In order to move the blocks in unison, I 100 mount a lever 23 on a lug 22 projecting from the cope section at each side of the flask. Each lever 23 has a hand hold 24 and rods 25 are connected to bolts 18 on the blocks 17. One rod is attached to the lever 23 on one side of the center and the other rod is attached to the lever on the opposite side of the center. When the lever is turned in one direction, the blocks 17 will be moved toward each other and when the lever is turned in the opposite direction, the blocks 110

17 will be moved away from each other and, as the sand retaining frame is attached to the blocks, it is either moved so as to project into the flask or is withdrawn clear of the sand of the flask for the purpose described hereinafter.

In order to draw the flask away from the pattern after the mold has been formed, I pivot levers 26 at 27 on opposite sides of 10 the flasks. The portions 28 of these levers extend through openings 28^a of the flange of the cope 1 and also extend through openings 28^a in the sand support 11; bearing upon the match board or the pattern support. 15 The opposite ends of these levers are forked, as shown in Fig. 11, and span the flanged eccentric 29 mounted on a pivot 30, projecting from the stud 22. This eccentric has a handle 31 and when this handle is 20 moved in the proper direction, the levers are projected or retracted, as desired.

In order to aline the cope section of the flask with the drag, I mount on the drag 2 a plate 32 having a triangular pin 33, 25 which projects through an opening in a bracket 34 on the cope. A plate 35, having a V-shaped end, is adjustably mounted on the bracket and neatly fits against the beveled edge of the pin 33. The plate can be secured 30 in the position to which it is adjusted by a screw, as clearly shown in Figs. 1 and 4. In some instances, a bridge piece 6 (indicated by dotted lines, Fig. 4,) is used in the sand and this bridge piece has legs 35 17 which extend to the lower edge of the cope section 1 and rest upon the sand support 11. This forms no part of the flask, being merely a means for retaining the sand in the proper position.

40 In making a mold with my improved molding flask, the steps are as follows:—If, for instance, a fire pot for a stove is to be cast, the cope is inverted and the pattern board—with the pattern also inverted—is placed 45 on the cope. The drag is then placed in position above the pattern board. Molding sand is introduced into the drag and when struck off, the bottom board is applied, after which the flasks are turned, as 50 shown in Fig. 13. The sand-retaining frame is then projected so as to extend into the flask; molding sand is introduced into the cope and rammed, as in Fig. 13. The cope is then bodily removed from the pattern 55 board and pattern by operating the cams 29; causing the levers 26 to press upon the board. and, as the cope is raised, Fig. 14, it carries with it the mold formed by the sand, as the projecting frame extends under the 60 mold. The pattern board, with the pattern is then removed from the drag and the cope, with its section of the mold, is placed upon the drag, with the two sand molds in contact, after which the sand supporting frame 65 is withdrawn, as in Fig. 15, so as to free

the mold section from the cope section of the flask, which is then removed, as in Fig. 15. The drag section of the flask is then free to be removed, leaving the two-part sand mold on the bottom board in position for the metal to be poured therein. Before the metal is poured, however, a frame is placed over the sand mold; thus dispensing with the weights and the ordinary frames usually employed, due to the fact that the 75 mold and the frame are tapered so as to retain the sand in position during the pouring operation.

If a pattern of greater height than could properly be handled in the cope section is 80 to be cast, then a supplemental section is clamped thereto to the height desired, as shown in Fig. 4. The height of this supplemental section varies, and, in fact, there may be a number of supplemental sections of different heights employed to 85 accommodate molds with patterns of different heights.

Where bridge pieces are necessary they are placed in the mold as shown by dotted lines, Fig. 4, and the legs 7 will rest upon the sand retaining frame 11, as it will be understood that these bridge pieces are made detachable from the cope and remain in the sand mold until after the metal has 95 been poured. They may be adapted to guides in the cope if desired.

In Figs. 12 and 17, I have shown a modification of the arrangements of the sections of the sand retaining frame. The side section 36 has an angle slot 37, in which extends a tongue 38 on the section 39. In place of the blocks, I connect an extension of the section 36 with a bar 40, which is loosely connected to the operating lever 23 so that, upon moving the operating lever, 105 the sections 36 will be moved in one direction and the sections 39 will be moved at right angles thereto.

I claim:

1. The combination in a flanged flask, of a sand support mounted on the flask, said support being made in four sections arranged to slide on the flask, one of said sections being perforated and the others being slotted; blocks arranged to slide on the flange of the flask, each block having two pins, one pin of each block entering the perforation in one of said sections, the other pin entering a slot in one of the other sections; and means for moving the blocks in unison so as to cause the support to be projected beyond the inner line of the flask and to be retracted.

2. The combination of a flask made in two sections; each section having flanges; a sand support slidably mounted on one end of one section; said sand support being made in four sections; blocks arranged to slide on the lower flange of the said section on which the

110

115

120

125

130

sand support is mounted; each block having pins engaging the said sections of the sand support; levers pivotally mounted on opposite sides of the flask; rods connecting the levers with the sliding blocks so that when the levers are operated the sand support will be projected or retracted.

3. The combination in a flask; of a sand support mounted at one end of the flask; means for retracting the sand support; levers on opposite sides of the flask; and cams for actuating the levers so as to raise the flask, with its sand mold, clear of the match board and of the pattern.

15 4. The combination in a flask, of a flanged cope section; a flanged extension thereon, one of said parts having undercut lips adapted to engage the flanges of the other part; and a pin for locking the two 20 parts of the flask together.

5. The combination of a flanged cope section; an extension mounted thereon; undercut lips on three sides of the extension engaging the flange of the cope section; with 25 a pin adapted to a way in the extension and arranged to rest upon the flange of the cope section, whereby the two sections are firmly locked together.

6. The combination in a flanged flask, of two levers pivoted thereto, each lever 30 having a portion extending through an opening in the flange of the flask; and an eccentric pivotally mounted on the flask and engaging the levers so that, when the eccentric is turned, the levers will be turned 35 on their pivots.

7. The combination in a flask, of two levers pivotally mounted on the flask and each having an extension on one side of the pivot; said levers being forked on the 40 opposite side of the pivots; a flanged eccentric pivotally mounted on the flask and engaging the forked portions of the levers; and a handle on the eccentric by which it is turned so as to actuate the levers to lift 45 the flask.

In testimony whereof, I have signed my name to this specification, in the presence of two subscribing witnesses.
